UNITED STATES PATENT OFFICE.

JOHN E. NORQUEST, OF RICHMOND, VIRGINIA, ASSIGNOR TO P. LORILLARD COMPANY, OF NEW YORK, N. Y., A CORPORATION OF NEW JERSEY.

BUNCH-CARRIER FOR CIGAR AND CHEROOT MACHINES.

1,252,935.

Specification of Letters Patent.

Patented Jan. 8, 1918.

Application filed July 23, 1917. Serial No. 182,286.

To all whom it may concern:

Be it known that I, JOHN E. NORQUEST, a citizen of the United States, residing at Richmond, in the county of Henrico and 5 State of Virginia, have invented new and useful Improvements in Bunch-Carriers for Cigar and Cherooot Machines, of which the following is a specification.

This invention relates to certain novel and 10 useful improvements in cigar and cherooot machines of the general type shown in U. S. Letters Patent to Oluf Tyburg, No. 654,203, dated July 24, 1900, and No. 1,075,172, dated October 7, 1913. In machines of this class 15 a wrapper is first cut, then transferred to a wrapping mechanism in which a bunch has been automatically placed and the wrapped bunch, constituting the cigar or cherooot, is wrapped by the last mentioned mechanism 20 and then automatically transferred to a delivery point by an automatic bunch carrier. In operation, this automatic bunch carrier places the bunch or other material to be wrapped in the wrapping mechanism, and 25 also removes the wrapped product from the wrapping mechanism, and my invention has particular application to improvements in this automatic carrier for bringing the bunch to and taking the wrapped cigar or 30 cherooot from the wrapping mechanism. As at present constructed, and in its arrangement relative to the co-operating parts of the machine, certain disadvantages are incident to the ordinary automatic bunch carrier for performing the functions above 35 mentioned.

Briefly, and in general, the well known form of bunch carrier includes a horizontally disposed arm fastened at one end to a 40 vertical shaft which is intended to swing the arm back and forth in the arc of a circle, or between the bunch supplying conveyer and the wrapping mechanism, the free end of this arm terminating in an enlarged 45 head which is provided with two sets of retaining devices, one set being arranged to transfer the bunch to be wrapped to the wrapping mechanism and the other to remove the wrapped product therefrom. These 50 retaining devices usually embody gripping fingers which are closed and opened at pre-determined times to seize and release the bunch, or the cigar, as the case may be. Such fingers are usually actuated through

spaced arms or stops supported above the 55 bed of the machine, but separate from the bunch carrier itself, and owing to their construction and the function they must perform, present an exceedingly inconvenient and even dangerous arrangement, because it 60 frequently happens that an operator will have her hand caught or pinned between the swinging carrier head and these operating stops or arms, this resulting in the liability of, and frequently in serious 65 injury to the hand. Furthermore, the swinging carrier head naturally moves to a position above, or close to the bunch supplying conveyer in taking the bunches and in placing finished or wrapped cigars thereon, and 70 often times the operator, reaching into the space between this conveyer and the moving bunch carrier, will have the hand caught, or pinned between the carrier head and the conveyer, or parts of the machine adjacent 75 thereto; this also usually causing serious injury or mutilation of the hand of such operator. As above stated, this bunch carrier is swung by a vertical rock shaft, and so far as I am aware up to the time of my 80 invention, no means have been provided for automatically stopping the bunch carrier in the case of an emergency, as when an operator's hand is accidentally caught by the bunch carrier and an adjacent part of the 85 machine; it being necessary at the present time to manually disconnect or throw off the power mechanism or some part thereof.

Another disadvantage incident to the usual construction and arrangement of a 90 bunch carrier is that it and its co-acting parts take up considerable space, and present a complicated, involved construction.

It is my purpose to obviate the above mentioned disadvantages by so constructing my 95 bunch carrier and its co-acting parts that in case an operator's hand is accidentally caught between such carrier and an adjacent part of the machine, such carrier will be automatically and instantly disconnected 100 from its own actuating or power mechanism, thereby coming to a stop and preventing the mutilation, for instance, of the hand of an operator.

Furthermore, I have greatly simplified the 105 construction of the bunch carrier and its operating parts and have reduced the space occupied thereby, especially the width of

the space taken by the actuating devices for the bunch and cigar retaining devices of the carrier head.

Another object of my invention is to provide a bunch carrier which will embody the desired features of simplicity, efficiency and reliability, and which will operate positively and for long and continuous periods without necessitating reconstruction or repair.

With the above recited objects and others of a similar nature in view, my invention consists in the construction, combination and arrangement of parts set forth in and falling within the scope of the appended claims.

In the accompanying drawings,—

Figure 1 is a view in side elevation of a bunch carrier embodying my invention and showing the same in conjunction with certain related parts of the machine, such as the bunch support or conveyer.

Fig. 2 is a bottom plan view of the bunch carrier including a bunch carrying arm and head with its retaining devices and the swinging cam plate.

Fig. 3 is a top plan view of the same.

Fig. 4 is a cross sectional view taken on the line 4—4 of Fig. 1.

Fig. 5 is a longitudinal sectional view on the line 5—5 of Fig. 3.

Fig. 6 is a top plan view of the swinging cam plate.

Fig. 7 is a bottom plan view of the swinging cam plate.

Fig. 8 is a detail perspective view of the spring latch plate for connecting the bunch carrier arm to the vertical rock shaft for swinging the bunch carrier.

Fig. 9 is a detail perspective view of the operating end of the cam plate.

Fig. 10 is a detail perspective view of the guide arm intended to guide the wrapped cigars to and from their retaining devices at the head.

Fig. 11 is a detail perspective view of the top portion of the vertical tubular standard to which the vertical rock shaft extends and showing spaced operating stops for limiting the swinging movement of the cam plate.

Fig. 12 is a cross sectional view on the line 12—12 of Fig. 1 looking in the direction of the arrows.

Referring now to the accompanying drawings in detail, and more particularly to Fig. 1, the letter A indicates the tubular supporting post or standard, while B is the usual bunch or cigar carrying conveyer or support located adjacent thereto, merely herein conventionally and partially illustrated, as is also the lifting device C therefor. The upper end of the standard A is formed with a collar 1 over which loosely fits the bored end 2 of the swinging cam plate 3. A vertical rock shaft 4 which constitutes the operating shaft for the bunch carrier is housed by the sleeve A and pro-

jects above the latter and loosely receives the collar 5 at the end of the bunch carrier arm 6, this collar 5 seating upon the end 2 of the cam plate 3. Thus, it will be noted that instead of making the bunch carrier arm fast with the operating shaft 4, both this arm and the cam plate are loosely mounted, and in order to connect the same in operative relation with the shaft, or to be swung by the latter, I provide a spring latch plate 7, which lies above the collar 5 of the carrier arm, and is made fast with the shaft 4 in any suitable manner, such as by a nut 8, the outer end of this latch 7 carrying a locking dog 9 having a recess 10 which is adapted to grip the top edge of the vertical web 11 of the carrier arm 6, the sides of this dog being oppositely beveled as at 12. From this arrangement it will be understood that under ordinary working conditions, the latch plate will connect the carrier arm with the shaft 4 so that it may be swung by the latter, but should sudden pressure be exerted against the carrier arm, as by the catching of an operator's hand between the arm and an adjacent part of the machine, the web of the arm will be swung or disconnected from the back of the web so that the rock shaft 4 can no longer move the arm and the latter will of course stop its swinging movement, although the shaft 4 may continue to rock. The bevel sides of the dog of course permit the web of the bunch carrier arm to be easily swung back into connection again with the latch. As the bunch carrier arm 6 is swung back and forth by the shaft 4, the cam plate 3 will also swing therewith to a limited degree, the path of movement of this cam plate being determined in one direction by the adjustable stop pin 13 carried by the lug 14 at one side of the post A, and in the other direction by the similar adjustable stop pin 13' carried by the lug 14' at the opposite side of the post A, as more clearly shown in Fig. 11. This swinging movement of the plate 3 with the bunch carrier arm 6 is obtained by the depending stud 15 socketed in the under side of the bunch carrier arm 6 and having its free end projecting downward between a pair of bars 16 pivoted as at 17 on top of the cam plate 3, a relatively strong coil spring 18 connecting these two bars intermediate their ends, as shown in Fig. 6, and normally tending to draw the free ends of the bars toward each other.

In Fig. 3, one side edge of the cam plate 3 is shown in contact with the stop pin 13', the cam plate having been swung with the bunch carrier arm to this position by reason of the stud and bar connection between the cam plate and arm just described. Of course the pin 13' will prevent any further swinging movement of the cam plate, as will be understood by reference to Fig. 6, but

the shaft 4 will continue the swinging of the bunch carrier arm, the spring 18 expanding as the arm 16 rocks on its pivot 17 by the side pressure of the stud 15 against the bar. Likewise, the same action will take place when the bunch carrier arm and the cam plate swing in the opposite direction or toward the stop pin 13. In other words, while the swinging of the cam plate is limited by the stops 13 and 13', the bunch carrier arm may swing beyond these limits owing to the pivoted and spring tensioned mounting of the bars 16. On the return movement of the bunch-carrying arm toward the center of the cam plate, these bars 16 tend to center the stud 15 or to cause the parts to occupy the position shown in Fig. 6.

At the free end of the bunch carrier arm 6 is the bunch carrier head 19, which is formed at its rear end with a down-turned flange 20 and at its front with a down-turned bifurcated flange 21, this head carrying the retaining devices for the bunches 25 and the cigars, and also the guide for the cigars, which guide is best shown in detail in Figs. 4, 5 and 10. This guide comprises a wire or metal rod 22, one end of which is journaled as at 23 to the front end of the 30 web 11, shown in Fig. 3, this rod then extending longitudinally in rear of the other head, is journaled as at 24 at the rear end of the head and terminates at its rear end in a crank 25, which projects between the 35 segmental cam blocks 26 and 26', fastened to the top of the cam plate 3 adjacent the front arcuate edge thereof. The confronting ends of these blocks 26 and 26' are spaced apart and oppositely beveled as shown at 27 and 40 27' respectively, these cam blocks being intended to actuate the crank end of the rod 22 so as to swing the curved guide arm 28 up an down in an arc, as will be understood by reference to Figs. 3 and 4, this guide 45 arm being adjustably mounted on the rod 22 by means of the set screw 30, and is tensioned by a coil spring 31 mounted about the rod 22 and connected at one end with the guide arm, as shown at 32, and at its 50 opposite end fastened to the body of the head as shown at 33 in Fig. 5. The cam blocks 26 and 26' coact with this crank actuated guide arm 28 to guide the wrapped cigars, that is to say, when a wrapped cigar 55 is being taken by its retaining device, as hereinafter described, this arm will be swung downward to prevent the cigar being thrown outward or dislodged, and when the wrapped cigar is being discharged from its 60 retaining device, this guide arm will move inward and guide the cigar downward onto its proper place on the carrier or conveyer B, the arm occupying its outward or inoperative position when the crank is between 65 the cam blocks 26 and 26'.

The head 19 carries the bunch-retaining and transferring device, indicated as an entirety by the letter D and also the cigar retaining and transferring device indicated as a whole by D'. The bunch carrying device 70 comprises a longitudinally extending inclined shaft 34, one end of which is journaled as at 35 in the jaw section 36 of the front flange of the head, while the rear end of this shaft extends through the jaw section 75 37 of the rear flange of the head, the rear free end of the shaft 34 carrying a short lug 38 extending at right angles to the shaft. The shaft 34 has also mounted thereon an arcuate finger 39 located adjacent the 80 jaw 36, the second arcuate finger 40 arranged adjacent the jaw 37, these fingers turning with the shaft to open and close on the bunch. Likewise, the cigar retaining device 85 D' comprises a longitudinally extending inclined shaft 34' journaled at its forward end as at 35' in the jaw section 36' of the front flange of the head and at rear end this shaft 34' projects through the upper portion of the jaw section 37' of the rear flange of the 90 head, these jaw sections 36' and 37' of the head being concave, as clearly shown in Figs. 1 and 2. The shaft 34' carries the arcuate fingers 39' and 40' arranged adjacent the jaw sections 36' and 37' respectively, 95 and these fingers are adapted of course to open and close on the wrapped cigars. The rear end of the shaft 34' is also formed with a small lug 38' similar to but offset or arranged in staggered relation to the lug 38 at the end of the shaft 34. Of course by 100 causing the shafts 34 and 34' to turn, the fingers 39 and 40 and 39' and 40' will be correspondingly operated or opened and closed. At the forward end of the head and in the bifurcation thereof is a pin 41, and a coil tension spring connection 42 extends between this pin and the finger 39, and a similar coil spring 43 also extends between this pin 41 and the finger 39'. These 105 springs are used to tension the retaining devices, in the sense that when the shafts 34 and 34' are rocked or turned to throw their respective fingers over or past a dead center 110 these springs will retain the fingers in such position until the shafts are again operated to turn the fingers in reverse direction, when the springs will act to hold the fingers in such second position after the dead center 115 has been passed. In other words, this well understood mechanical arrangement of the springs is simply for the purpose of holding the fingers in a position to which they have been moved by rocking them in either direction. The shafts 34 and 34' of the retaining devices D and D' are actuated or rocked by 120 cams located on the under side of the cam plate 3, as will be understood by reference to Figs. 1 and 2.

Considering Figs. 1 and 2, in the ma- 125

chine as actually constructed, the cigar retaining device D' having as a part thereof the guide frame, faces the wrapping mechanism, while the bunch-retaining device D faces the conveyer, the entire bunch carrier of course swinging in an arc or path between the wrapping mechanism and the conveyer, as is well understood in machines of this class. As the bunch-carrying arm 10 swings over the conveyer to pick up a fresh bunch and deliver a wrapped cigar, the bunch-retaining device D is operated by rocking the shaft 34 to close the bunch-carrying fingers 39 and 40 presented by the 15 conveyer, a segmental cam strip 44, on the cam plate 3, being employed for this purpose. It will be seen that the sweep of the bunch carrier head over the cam plate 3 after the latter has been brought to a stop 20 at the limit of its swinging movement, will cause the lug 38 at the end of the shaft 34 to contact with the cam 44 to close the fingers, grip the bunch and remove the latter from the conveyer to the wrapping mechanism with the travel of the arm. At the 25 same time when the cigar retaining device D' is positioned over the conveyer ready to deliver a cigar, which we may assume is clamped by the closed fingers 39' and 40', the cam-toe 47, in the present instance an integral part of the cam 44, will strike the lug 38' at the end of the shaft 34' and rock the lug so as to open the cigar retaining fingers 39' and 40', and release the cigar to 30 permit the latter to drop onto the conveyer, the guide arm 28 having been moved inward and downward into operative or guiding position to drop the cigar to its proper place of rest on the conveyer. Likewise, when 35 the carrier head has been brought into position above the wrapping mechanism by the swinging of the arm 6, the cam plate 3 having been brought to a stop, the continued movement of the arm 6 will cause the now 40 opened cigar retaining fingers 39' and 40' to be closed because the lug 38' at the end of the shaft 34' will contact with the segmental cam plate 46, rocking the shaft 34' to close the fingers about the wrapped cigar 45 at the wrapping mechanism, the guide arm 28 again being lowered into guiding position to prevent the escape of a cigar and to guide the same properly to the fingers as they close. The head now continuing its 50 movement over the wrapping mechanism, the lug 38 at the end of the shaft 34 of the bunch-retaining device D will strike the cam 45 on the cam plate 3 and open the fingers 39 and 40, thus depositing the bunch or 55 feeding the latter to the wrapping mechanism. This sequence of movements, or cycle of operation, of course continues for, as will be readily understood, in the assembled machine, the bunch carrier is so positioned relative to the conveyer or traveling support 60

for the bunches and the wrapping mechanism as to swing back and forth, moving into position relative to the conveyer to receive a bunch from the latter and to deliver a wrapped bunch or cigar thereto, and then 70 moving to a position with respect to the wrapping mechanism to receive a wrapped bunch therefrom and to deliver an unwrapped bunch thereto. Consequently, the bunch-retaining device D should be opened 75 at the time it receives the bunch and should be closed immediately thereafter and should be opened to deliver the bunch to the wrapping mechanism. This is accomplished by the cam arrangement on the cam plate here- 80 tofore described. Similarly, the cigar retaining device D' which carries the wrapped bunch or cigar should be opened at the time it is about to receive the cigar and should be closed at the time it is about to deliver 85 the wrapped bunch or cigar to the conveyer. The cigar retaining device D' thereafter is controlled and operated by its own particu- 90 lar cam arrangement on the cam plate 3, as before mentioned. So far as the cigar retaining device D' is concerned, the cigar in being picked up and deposited by the fingers of its retaining device is guided and pre- 95 vented from falling away by the swinging or rocking guide arm 28, as before de- 100 scribed. It will be noted that at each side of the center longitudinal line of the cam plate 3 is a pair of cam members, one mem- 105 ber of each pair being to open one of the retaining devices, while the other member of such pair is to close the other retaining device.

The general principles upon which the bunch carrier operates will be readily understood from the above description, especially 105 when taken in connection with the disclosure contained in U. S. Letters Patent to Oluf Tyberg, No. 654,203 and No. 1,075,172, hereinbefore mentioned.

While I have herein shown and described 110 one particular embodiment of my invention, I wish it to be understood that I do not limit myself to all the precise details of construction herein set forth by way of illustration, as modification and variation may 115 be made without departing from the spirit of the invention or exceeding the scope of the appended claims.

What I claim is:

1. In a cigar or cheroot machine, a traveling carrier provided with a retaining device for a tobacco roll, a plate-like member traveling with the carrier, means detachably connecting said carrier and member, and means carried by said member for opening 120 and closing the retaining device at predetermined times.

2. In a cigar or cheroot machine, a traveling carrier movable in a path having a defined length, said carrier having a retain- 130

- 5 ing device on the carrier arm, a member also 65
 traveling with the carrier but moving in a path
 of relatively different defined length than
 the path of the carrier, means detachably
 connecting the carrier and the member, and
 means carried by said member for opening
 and closing the retaining device of the car-
 rier at predetermined times. 70
- 10 3. In a cigar or cheroot machine, an os-
 cillating carrier arm, a retaining device for
 a tobacco roll carried by said arm and an
 oscillating member moving with and beneath
 the carrier arm and having means adapted
 to open and close the retaining device at
 15 predetermined times. 75
- 15 4. In a cigar or cheroot machine, a swing-
 ing carrier arm, a retaining device for a to-
 bacco roll carried by the carrier arm, a
 swinging member independent of and mov-
 20 able substantially in parallelism with the
 carrier arm, and means carried by said mem-
 ber for opening and closing the retaining
 device at predetermined times. 80
- 25 5. In a cigar or cheroot machine, the com-
 bination with a power shaft, of a swinging
 carrier arm connected with said shaft, a
 swinging plate also mounted on the shaft in-
 30 dependent of the carrier arm and adapted to
 swing substantially in parallelism with said
 carrier arm, cam members on said swinging
 plate and a retaining device for a tobacco
 35 roll carried by the carrier arm and adapted
 to be opened and closed by the cam mem-
 bers. 85
- 40 6. In a cigar or cheroot machine, a hori-
 zontally swinging carrier having a retain-
 ing device for a tobacco roll, and a hori-
 zontally swinging cam plate having cam mem-
 bers adapted to open and close the retaining
 45 device at predetermined times. 90
- 45 7. In a machine of the class described, a
 traveling carrier provided with a retaining
 device, actuating means movable with the
 traveling carrier to a limited degree for
 opening and closing the retaining device, a
 50 power element to which said traveling car-
 rier and actuating means are loosely con-
 nected, and means for releasably connect-
 ing the traveling carrier in driven relation
 with the power element. 95
- 55 8. In a machine of the class described, the
 combination with a power shaft, of a trav-
 eling carrier loosely mounted thereon, a re-
 taining device supported on the carrier, a
 cam plate also loosely mounted on the power
 60 shaft and having cam members for opening
 and closing the retaining device, said cam
 plate being movable with the carrier to a
 limited extent, and means detachably con-
 necting the carrier in driven relation with
 65 the power shaft. 100
- 65 9. In a machine of the class described, the
 combination with a power shaft, of a car-
 rier arm loosely mounted thereon, a retain-
 ing device on the carrier arm, a member also
 loosely mounted on the power shaft pro-
 70 vided with cam members adapted to open
 and close the retaining device at predeter-
 mined times, and means for releasably con-
 necting the carrier arm with the power
 shaft, and a yielding connection between the
 75 carrier arm and the cam carrying member. 105
- 80 10. In a machine of the class described,
 the combination with a power shaft, of a
 swinging carrier arm loosely mounted there-
 on, a swinging plate also loosely mounted
 on the shaft and provided with cam mem-
 bers, a retaining device carried by the car-
 85 rier arm and adapted to be opened and
 closed by the cams, a connection between the
 carrier arm and the cam plate, and
 means for connecting the carrier arm to the
 power shaft whereby said carrier arm and
 cam plate may be moved by the shaft, said
 means being operable to release the carrier
 arm from driven relation with the shaft
 under certain conditions. 110
- 85 11. In a machine of the class described,
 the combination with a power shaft, of a
 carrier arm loosely mounted thereon, a plu-
 rality of retaining devices supported from
 the carrier arm, one retaining device being
 adapted to receive and discharge a bunch
 and the other retaining device being adapt-
 ed to receive and discharge a wrapped cigar,
 90 means loosely mounted on the power shaft
 for independently actuating the retaining
 device, means connecting the carrier arm
 with the actuating means, and means fast
 95 with the power shaft and detachably engag-
 ing the carrier arm for releasably connect-
 ing such carrier arm with the power shaft. 100
- 100 12. In a machine of the class described,
 the combination with a power shaft, of a
 carrier arm mounted to swing thereon, a
 plurality of retaining devices carried by
 the carrier arm, a cam plate also mounted on
 the power shaft and provided with a plu-
 rality of cams for independently operating
 the retaining devices at predetermined times,
 105 and means connecting the carrier arm with
 the cam plate. 110
- 110 13. In a machine of the class described,
 the combination with a power shaft, of a
 cam plate mounted to swing thereon and
 provided with a plurality of cams, means
 for limiting the swinging movement of the
 cam plate in two directions, a carrier arm
 also loosely mounted on the shaft, a con-
 nection between the carrier arm and the
 cam plate, whereby both carrier arm and the
 115 cam plate may be moved together for a lim-
 ited distance, the connection between the
 cam plate and the arm permitting further
 movement of the arm after the cam plate
 has been brought to a stop, a releasable con-
 nection between the power shaft and the
 carrier arm, and a plurality of retaining
 120 devices. 125

devices carried by the carrier arm and independently operable by the cams of the cam plate.

14. In a machine of the class described, the combination with an operating shaft, of a swinging cam plate thereon, means for limiting the swinging movement of the cam plate, a carrier arm also swinging on said shaft, means connecting the carrier arm with the cam plate and permitting further movement of the carrier arm after the cam plate has been brought to a stop, a retaining-device carried by the carrier arm, and means on the cam plate for operating the retaining device to grasp and release an article at predetermined times.

15. In a machine of the class described, the combination with a power element, of a traveling arm carried thereby and provided with a retaining device, an actuating member connected with said shaft adapted to operate the retaining device to receive and discharge an article, and a yieldable connection between the actuating member and the traveling arm, whereby said actuating member is caused to travel a limited distance with the traveling arm.

16. In a machine of the class described, the combination with an operating shaft, of a traveling carrier loosely connected therewith provided with a retaining device for grasping, holding and discharging an article, and a connection between the shaft and the traveling carrier operable when pressure is applied to the carrier to release the carrier from driven relation with the shaft.

17. In a machine of the class described, a traveling carrier, provided with a cigar-retaining device and a bunch-retaining device, actuating means traveling with the carrier for opening and closing both the retaining devices, means for limiting the travel of the actuating means, and means

constituting a connection between the traveling carrier and the actuating means adapted to permit further movement of the carrier after the actuating means has been brought to a stop.

18. In a machine of the class described, the combination with a traveling carrier, of a retaining device carried thereby, a movable guide co-operating with the retaining device and an actuating member movable with the traveling carrier for opening and closing the retaining device and for moving the guide into and out of guiding position relative to the retaining device at predetermined times.

19. The combination with an operating shaft, of a carrier arm loosely mounted on the shaft, a releasable connection between the carrier arm and the shaft for placing said carrier arm in and out of driven relation with the shaft, a cigar-retaining device and a bunch-retaining device carried by the carrier arm, each of said devices including a rocking shaft, and a pair of fingers mounted thereon, a cam plate also loosely mounted on the shaft beneath the carrier arm, said cam plate carrying cam members adapted to actuate the rocking shafts of the retaining devices to open and close the fingers at predetermined times, a connection between the carrier arm and the cam plate whereby said cam plate will be caused to travel with the carrier arm a predetermined distance, said connection including or comprising a stud, a plurality of pivoted bars between which the stud projects, and a spring connecting said bar, and stop members for limiting the travel of the cam plate, the connection between the cam plate and the carrier arm permitting the further movement of the arm.

In testimony whereof I have hereunto set my hand.

JOHN E. NORQUEST.
